US00D828125S

(12) **United States Design Patent** (10) **Patent No.:** **US D828,125 S**
(45) **Date of Patent:** **** Sep. 11, 2018**

(54) **HANDLE FOR LAWN AND GARDEN TOOL**

- (71) Applicant: **THE TORO COMPANY**,
Bloomington, MN (US)
- (72) Inventors: **Philip C. Dretzka**, Woodbury, MN
(US); **Ryan J. Sweere**, Minneapolis,
MN (US); **Tyler E. Peterson**,
Lindstrom, MN (US); **David J. Martin**,
Eden Prairie, MN (US)
- (73) Assignee: **THE TORO COMPANY**,
Bloomington, MN (US)
- (**) Term: **15 Years**
- (21) Appl. No.: **29/592,487**
- (22) Filed: **Jan. 31, 2017**
- (51) LOC (11) Cl. **08-03**
- (52) U.S. Cl.
USPC **D8/8**; D8/316
- (58) **Field of Classification Search**
USPC D8/8, 315-320
CPC E05Y 2900/531; B25F 5/026; B62D 43/10
See application file for complete search history.

(57) **CLAIM**

The ornamental design for a handle for lawn and garden tool, as shown and described.

DESCRIPTION

FIG. 1 is a top left perspective view of a handle for lawn and garden tool in accordance with the claimed design and shown as part of a string trimmer;

FIG. 2 is a top left perspective view of the design of FIG. 1; FIG. 3 is a bottom right perspective view of the design of FIG. 1;

FIG. 4 is a left side elevation view of the design of FIG. 1; FIG. 5 is a right side elevation view of the design of FIG. 1; FIG. 6 is a top plan view of the design of FIG. 1; and, FIG. 7 is a bottom plan view of the design of FIG. 1.

Front and rear elevation views of the design of FIG. 1 are omitted as being unnecessary and/or cumulative in view of the remaining figures.

The dash-dash broken lines in the figures represent environment and form no part of the claimed design.

The dot-dash broken lines in the figures immediately adjacent the solid lines represent a boundary between claimed and unclaimed subject matter and form no part of the claimed design.

1 Claim, 7 Drawing Sheets
